UNITED STATES PATENT OFFICE

2,545,381

ELECTRIC QUESTIONNAIRE GAME

James M. Prentice, South Hadley, Mass.

Application January 24, 1949, Serial No. 72,330

2 Claims. (Cl. 35—9)

1

This invention relates to improvements in game apparatus.

The principal object of the invention is the provision of a game apparatus which is characterized by mechanical and electrical means which cooperate to provide a game that is interesting in play as well as being educational.

The apparatus of the invention may be adapted for various games and rules of play but will be described as a "True or False" game for purposes of disclosure.

With the foregoing and various other novel features and advantages and other objects of my invention as will become more apparent as the description proceeds, the invention consists in certain novel features of construction and in the combination and arrangement of parts as will be hereinafter more particularly pointed out in the claims hereunto annexed and more fully described and referred to in connection with the accompanying drawings wherein:

Fig. 1 is a plan view of a game embodying the novel features of the invention.

Fig. 2 is a side elevational and sectional view on the line 2—2 of Fig. 1.

Fig. 3 is a plan view of the circuit changing member of the game, and

Fig. 4 is a circuit diagram of the game.

Referring now to the drawings more in detail, the invention will be fully described.

A box 2 has side, end and bottom walls 4, 6 and 8 and a supporting wall 10 spaced upwardly from the lower wall 8.

The wall 10 has delineated thereon statements such as "Ebony is black" which are designated by numerals, all as shown. Also the wall 10 carries "True or false" and "You are right." Yieldable metallic switch closing members 12 and 14 adjacent "True" and "False" have outer ends secured to wall 10 by rivets 16, or the like.

Inner ends of the said circuit closing members have metallic contacts such as 18. When members are depressed the contacts 18 are moved through holes such as 20 provided in said wall 10.

A circuit changing member preferably in the form of a disc is provided and is shown at 24 in Fig. 3. This disc may be made from cardboard and has a metallic sheet or disc 26 thereon over which is a paper sheet 28.

The members 24, 26 and 28 may be secured together in any well known manner. A hollow metallic eyelet 30 extends through the members with the metallic sheet and eyelet making an electrical contact.

An eyelet 32 of wall 10 extends through the eye-

2

let 30 of the member 24 whereby the said member 24 is rotatable beneath wall 10.

A slot 34 is provided in wall 10 so that the periphery of member 24 is accessible for rotation thereof by manual engagement.

The member 24 carries numerals 1, 2, 3, etc., as shown, which may be indexed with a window 36 through the wall 10.

The upper sheet 28 of member 24 is provided with openings therethrough as indicated by 38 and 40. These are arranged in spaced apart relation in concentric circumferential rows and provide contact portions or contacts 38' and 40' all connected to one common terminal 30. These openings 38 and 40 are arranged to underlie the contacts of circuit closing members 12 and 14 so that when a member 12 or 14 is depressed the contact thereof may contact a contact of the sheet 26 of member 24.

20 Discs 42 are provided on the contacts of levers 12 and 14 which engage the wall 10 when a contact member is depressed to limit downward movement thereof.

A battery is shown at 44 a portion of which 25 may extend through an opening 46 of wall 10.

A yieldable metallic contact 48 has one end 50 in electrical contact with eyelet 30 of the member 24 and is fixed by a rivet 52, or the like, to wall 10. An opposite end 54 of member 48 carries 30 a socket 56 in which is an electric bulb 58. The components are electrically connected as will be described in connection with Fig. 4.

The circuit closing members 12 and 14 are connected by 60 to one side of battery 44 and the 35 other side of the said battery is connected by 62 to the lamp 58. The member 48 is connected to the lamp 58 and as described is in contact with rivet 30 which is in contact with the metallic sheet 26 of member 24.

40 In all cases the numerals and openings 38 and 40 will be arranged in such relationship that the lamp 58 will be energized only when one has indicated by the correct circuit closing member that the statement is right.

45 The game in the form of the invention shown and described is operated in the following manner.

One selects a stated fact such as 3 "A skyscraper is an airplane" and turns the member 24 50 so that 3 is indexed in the window 36. Then the player depresses either contact 12 or 14 depending upon whether he thinks the statement is true or false.

The holes 38 and 40 of member 24 are so disposed with relation to 3 on said member that if

contact 14 is depressed the contact of the said member will contact the metallic disc 26 of member 24 to complete a circuit and light lamp 58 wherefor the answer will be "you are right."

There will be no hole through which the contact of member 12 may contact the metallic sheet 26 so that if member 12 is depressed the lamp will not be lighted.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description.

What it is desired to claim and secure by Letters Patent of the United States is:

1. A game apparatus comprising in combination, a support, a circular member rotatable relative to and spaced below said support and having radially spaced rows of circumferentially spaced electrical contacts, separate circuit closing members secured to the upper side of said support having contacts, said support having an opening for each circuit closing member contact therethrough with which the contacts of said circular member are registrable, said circuit closing members being depressible to extend the contacts thereof through the openings of said support into contact with the contacts of said circular member, an electric light, a source of electrical energy, connections between said source of energy and the contacts of said circular member and said light, and connections between said contact members and source of energy whereby said light may be energized as one of said contacts engages a contact of the circular members having a contact in register with an opening of the support.

2. Game apparatus comprising in combination, a support, a circuit changing member mounted for rotation beneath said support and carrying indexing indicia and radially spaced circumferentially arranged rows of spaced contacts, said indicia and contacts having a certain relationship, said support provided with a window with which said indicia may be registered and having separate openings with which certain contacts of said circuit changing member register when certain related indicia is in register with the window of said support, a circuit closing member for each said opening fixed to the upper side of said support and being depressible into contact with the contacts of said circuit changing member through the opening of said support, an electric light, a source of electrical energy, connections between the said contacts of the circuit changing member and said light and said source of energy, and connections between said circuit closing members and source of energy, all adapted and arranged whereby said light is energized only when certain ones of said circuit closing members are depressed and said circuit changing member presents a certain contact to a certain opening.

JAMES M. PRENTICE.
